UNITED STATES PATENT OFFICE.

WALTER I. HILL, OF CLARKSBURG, WEST VIRGINIA.

TINNING APPARATUS.

No. 901,900.

Specification of Letters Patent.

Patented Oct. 20, 1908.

Application filed March 3, 1908. Serial No. 418,997.

To all whom it may concern:

Be it known that I, WALTER I. HILL, a citizen of the United States of America, residing at Clarksburg, in the county of Harrison and State of West Virginia, have invented new and useful Improvements in Tinning Apparatus, of which the following is a specification.

This invention relates to tinning apparatus, and the object of the invention is to provide means for supplying the oil used in the tinning process to the rolls between which the sheets are passed during the operation of rolling the coating of tin upon the opposite surfaces of the sheets.

With the above general object in view, the invention consists in the novel construction, combination and arrangement hereinafter fully described, illustrated and claimed.

20 In the accompanying drawing,—Figure 1 is a view partially in elevation and partially in section, showing the improved apparatus. Fig. 2 is a section taken at right angles to Fig. 1, illustrating the tinning rolls. Fig. 3 is a vertical sectional view of the oil tank, taken on the line 3—3 of Fig. 4, showing the pumping mechanism. Fig. 4 is a section through the same taken at right angles to Fig. 3. Fig. 5 is an enlarged longitudinal 25 section through the pump cylinder. Fig. 6 is a longitudinal section through the piston.

Referring to the drawing, and particularly Fig. 1, 1 and 2 designate the tinning rolls or, in other words, the rolls between 30 which the sheets are passed after they have been treated with the tinning solution, the said rolls operating to press the coating of tin and roll the same in close contact with the sheets. These rolls are arranged parallel 35 to each other and in very close relation, as shown in Fig. 1, and are mounted in suitable bearings in a receptacle 3 containing the tinning solution, the said rolls being journaled at their opposite ends in suitable bearings, 40 as indicated at 4.

Palm oil is generally used in the process 45 of tinning sheet metal, and in order to keep said oil clean and avoid staining the tinned sheets, it is necessary to keep up a constant supply of fresh oil and furthermore to keep 50 said oil at a certain temperature. It is desirable to apply this clean fresh oil just as the sheets pass between the tinning rolls 1 and 2, and in order to accomplish this I 55 provide at each end of the pair of rolls 1 and 2 nips or guards 5 which fit closely to the ends

of the rolls and are let into rabbets at the opposite ends of the rolls, which rabbets are formed by reducing the extremities of the rolls, as indicated by dotted lines in Fig. 1. 55 In this way a substantially V-shaped trough is formed between the rolls and the nips or guards, so that a constant supply of oil is deposited upon both surfaces of the sheets as they pass through the space between the 60 rolls. In order to apply this constant flow of oil, I provide at a suitable distance from the rolls an oil tank 6 which may be of any desired capacity and from which an oil pipe 7 extends to the receptacle 3 in which the 65 tinning rolls are mounted. After entering the receptacle 3 the pipe 7 is carried downward along the bottom of the receptacle and beneath the rolls 1 and 2.

About centrally of the length of the rolls 70 1 and 2 the pipe is provided with an up-standing terminal portion 8, the extremity of which is arched over one of the rolls, as shown at 9, so as to discharge the contents of the pipe into the trough formed between the 75 rolls and the nips.

About centrally of the length of the rolls 80 1 and 2 the pipe is provided with an up-standing terminal portion 8, the extremity of which is arched over one of the rolls, as shown at 9, so as to discharge the contents of the pipe into the trough formed between the 85 rolls and the nips. Oil is forced through the pipe 7 to the tinning rolls by means of a pump located within the tank 6 and embodying a pump cylinder 10 in which operates a piston 11. This piston reciprocates back and forth in the pump cylinder and is provided with a central longitudinal bore 12 forming a vacuum relief passage, the same being intermittently 90 opened and closed at its inner end by means of a check valve 12, shown in the form of an ordinary flap valve. About midway of the length of the pump cylinder the latter is provided with an oil inlet port 14 which opens directly into the body of the tank 6, as shown 95 in Fig. 4. At its discharge end the pump cylinder is provided with a check valve 15, preferably in the form of a ball, the same being held to its seat by means of a spring 16. The pump cylinder is also provided 100 with a coupling or union 17 to which the adjacent end of the pipe 7 is connected.

The piston 11 has connected thereto one arm 18 of a rock shaft 19 journaled in suitable bearings in the tank 6 and having the 105 other arm 20 thereof adjustably connected to a rod 21 which is connected to an eccentric strap 22 embracing an eccentric 23 on the shaft 24 of a spur gear wheel 25 which meshes with and is driven by a pinion 26 on a shaft 27 which leads outward through one side of the tank, where it is provided with a

5 pulley 28 to which power may be delivered by a suitable driving belt 29 extending to a motor of any description. The arm 20 of the rock shaft 19 is provided with a longitudinal series of holes, as shown in Fig. 4, so that the adjacent end of the rod 21 may be adjusted toward and away from the shaft 19 for the purpose of increasing or decreasing the stroke of the piston 11 and consequently the rapidity of feed of the oil to the tinning rolls.

10 In making tin plate, the sheet has to be run through the metal and up through the rolls which act to press the metal on to the sheet. In the ordinary construction of apparatus for this purpose the rolls are run in palm oil, and this oil is kept in a highly heated condition; therefore, the oil burns away rapidly and also gets very dirty, and 15 fresh oil must necessarily be put on the rolls so as to clean the plates, this being usually done by dipping oil out of a small receptacle hanging in convenient relation to one side of the machine. Under the arrangement 20 hereinabove described oil is fed automatically and with any desired rapidity to the

uppermost tinning rolls and acts to keep the surfaces of the tinned sheets clean and bright. In actual practice it has been found that a very great saving in oil is effected as compared with the old process.

Having thus described the invention, what is claimed as new, is:—

1. The combination with tinning rolls, and a receptacle for oil in which said rolls are mounted, of a force-feed oil pipe leading from a point of supply downward beneath the rolls and upward above the plane of said rolls and adapted to discharge oil into the space between the rolls.

2. The combination with tinning rolls having rabbeted ends, of nips or guards, means for yieldingly holding said nips into engagement with the rabbeted ends of the rolls, and a force-feed oil pipe arranged to discharge oil into the pocket formed by the rolls and nips.

40 In testimony whereof I affix my signature in presence of two witnesses.

45 WALTER I. HILL.
